ABSTRACT

There is disclosed an evanescent mode waveguide mixer. A first length of evanescent mode waveguide is provided having one end coupled to a signal source and the other end coupled to a local oscillator. A resonant slot, either a longitudinal or a transverse resonant slot, is provided intermediate the two ends of the first length of waveguide so that the first length of waveguide between the resonant slot and the signal source constitutes an evanescent mode filter for coupling the signal of the signal source to the resonant slot and so that the first length of waveguide between the resonant slot and the local oscillator constitutes an evanescent mode filter for coupling the signal of the local oscillator to the resonant slot. A second length of waveguide is disposed at right angles to the first length of waveguide and disposed to receive energy through the resonant slot. A mixer diode is disposed in the second length of waveguide closely adjacent the resonant slot. The second length of waveguide is dimensioned to be evanescent at the mixer generated frequency and propagating at the mixer generated sum frequency. Reactance components are provided in the second length of waveguide beyond the mixer diode to provide independent adjustment to terminate the image and sum frequencies.

WAVEGUIDE MIXER

BACKGROUND OF THE INVENTION

This invention relates to a waveguide mixer arrangement.

As is well known, the basic mixing process generates a number of frequencies of which the following are important in the present invention. Calling the signal and local oscillator frequencies f_s and f_o , respectively, the generated frequencies include

$f_s - f_o$ (the intermediate frequency f_{IF})

$f_s + f_o$ (the sum frequency)

$2f_o - f_s = f_o + (f_o - f_s) = f_o \pm (f_{IF})$ (the image frequency).

In a mixer circuit in which the signal source includes a unidirectional device such as a circulator or isolator, and the isolator is coupled directly to the mixer, both the sum and image frequencies will be completely absorbed in the isolator.

In general, the properties of isolators make them desirable in applications where the input match must be maintained independently of minor changes in the characteristics of the mixer diode. If these advantages are to be retained with the improved conversion loss which is obtained by reactively terminating the image frequency, a more complex circuit is necessary. The necessary addition comprises a bandstop filter located between the isolator and the mixer and tuned to the image frequency. Such a circuit is well known in the waveguide art, but has some disadvantages. The most serious disadvantage is that in practice it is possible to terminate reactively the image frequency only. At the sum frequency the waveguide is overmoded and at least two or more modes will exist in the waveguide. Thus, a satisfactory termination of the sum frequency is not possible and in certain cases additional problems in the group delay characteristics of the mixer arise from this. A further disadvantage results from the additional bandstop filter required which contributes to the complexity of the circuit.

SUMMARY OF THE INVENTION

An object of the present invention is to permit reactive termination of both the image and the sum frequencies in a waveguide mixer arrangement.

Another object of the present invention is to permit variation of the electrical characteristics of the waveguide mixer arrangement in a simple manner over a wide range of impedances.

A feature of the present invention is the provision of a waveguide mixer arrangement comprising a first waveguide, one end of which receives an input signal having a first given frequency and the other end of which receives a local oscillator signal having a second given frequency different than the first given frequency; a first resonant slot disposed in one wall of the first waveguide intermediate the ends thereof; the first waveguide including a first evanescent mode waveguide filter to couple the input signal to the first resonant slot, and a second evanescent mode waveguide filter to couple the local oscillator signal to the first resonant slot; a second waveguide coupled at right angles to the first waveguide encompassing the first resonant slot, the second waveguide being dimensioned to be evanescent at the mixer generated image frequency and propagating at the mixer generated sum frequency; a mixer diode disposed in the second waveguide adjacent to the first resonant slot; a capacitive obstacle disposed

in the second waveguide a first given distance from the first resonant slot to provide within the second waveguide an evanescent mode resonator tuned to the image frequency so as to effect reactive termination of the image frequency; and a short circuit plate disposed in the second waveguide, a second given distance greater than the first given distance from the first resonant slot to effect reactive termination of the sum frequency.

BRIEF DESCRIPTION OF THE DRAWING

The above-mentioned and other features and objects of this invention will become more apparent by reference to the following description taken in conjunction with the accompanying drawing, in which:

FIG. 1 is a side view of a waveguide mixer arrangement in accordance with the principles of the present invention;

FIGS. 2 and 3 are, respectively, a sectioned plan view taken along line B-B of FIG. 1 and an enlarged sectioned end view taken along line A-A of FIG. 1;

FIGS. 4 to 9 illustrate successive stages in presenting the principle of operation of the mixer arrangement of the present invention;

FIG. 10 shows the performance characteristic of a mixer diode mount;

FIGS. 11 and 12 relate to theory establishing tests for the mixer operation; and

FIG. 13 indicates an alternative slot arrangement for the mixer arrangement of the present invention.

DESCRIPTION OF THE PREFERRED EMBODIMENT

The mixer arrangement shown in FIGS. 1, 2 and 3 is designed for operation at a signal frequency (f_s) of 7.570 GHz (gigahertz) and a local oscillator frequency (f_o) of 7.500 GHz. The intermediate frequency (f_{IF}) is 0.070 GHz, the sum frequency ($f_s + f_o$) is 15.070 GHz, and the image frequency ($2f_o - f_s$) is 7.43 GHz.

The basic mixer arrangement comprises a flanged length of rectangular cross-section waveguide 1 which is so dimensioned as to have a cut-off frequency above the frequencies of both the signal and the local oscillator. Extending into the waveguide from the lower broadwall thereof are capacitive screws 2. In the upper broadwall are two longitudinal narrow slots 3 and 4 each centered on the respective transverse center line of two capacitive screws 2. A mixer diode 5 is mounted closely adjacent the plane of slot 3. Extending from each of slots 3 and 4 are waveguide lengths 6 and 7, each of rectangular cross-section, each containing an adjustable capacitive screw 8 and 9, respectively, and each terminated by a conducting plate 10 and 11, respectively. The nature and function of these two arms will be described later in detail, but it may be stated here that these two arms constitute, respectively, image and sum frequency reactive terminating circuits, and a rejection filter for the local oscillator frequency.

The input signal having a frequency f_s is fed into the left hand end of waveguide 1, and the local oscillator signal having a frequency f_o is fed into the right hand end of waveguide 1. Energy transfer through the waveguide at the respective frequencies is achieved by adjusting the depth of penetration of the capacitive screws 2 so that the waveguide sections on either side of the mixer diode 5 function as evanescent dominant mode bandpass filters centered, respectively, on the

input signal and local oscillator signal frequencies. The basic functioning of such filters is more fully described in British Pat. No. 1,129,185.

With regard to the filter for the input signal, this has a two-fold purpose. It is convenient to have a short length of waveguide between the mixer and the input flange, where connection to the signal isolator is made. This section must be resonated in order to effect power transfer. However, the filter satisfies a more basic purpose in providing a broad band harmonic rejection filter, which provides protection from undesired frequencies (say above 10 GHz in the present example) which would otherwise pass through the transparent (at these frequencies) signal filter and mix with harmonics of the local oscillator to produce an undesired I.F. signal. A broad passband of signal and image frequencies ensures that the source impedance, as seen by the mixer, at signal and image frequencies, is essentially that of the isolator connected at the input flange.

With mixer diode 5 suitably matched to the two frequencies, the input signal frequency and the local oscillator signal frequency, the basic technique of matching a mixer diode mount in evanescent mode waveguide filters being more fully described in British Pat. No. 1,187,283, the resulting intermediate frequency is derived from mixer diode 5 via a low pass filter 12 in a coaxial output connector 13.

Before describing the image terminating technique, an understanding of the principles on which the mixer mount functions is necessary. This can be obtained with the aid of FIG. 4 which shows diode 5 mounted across the narrow longitudinal slot 3 in the broad wall of waveguide 1. The effect of the slot in the guide can be better understood by considering evanescent mode resonance from a slightly different standpoint from that of the above first-mentioned British patent.

If one considers a thin slice of cut-off waveguide along its transverse axis, FIG. 5, it may be considered as a transmission line less than half a wavelength long (because it is below cut-off). By adding a capacitance C, FIG. 6, the electrical length can be increased until it is a half wavelength long, i.e., $\theta + \phi = \lambda/2$, where θ = the electrical length of the waveguide and ϕ = equivalent electrical length contributed by C, resonance will be modified somewhat by the environment on either side. This is the fundamental way in which resonance occurs. Although this is simply a way of describing a phenomenon which may be described more accurately by other means, it is a viewpoint that leads to new configurations. For example, a transmission line which is shorter than a half wavelength may be brought to the resonant half-wave condition by adding series inductance, FIG. 7, where $2(\theta/2 + \phi_1) = \lambda/2$. This "series inductance" required to realize the transverse resonance in cut-off waveguide may be obtained by a short (less than $\lambda/2$) longitudinal slot, FIG. 8.

It will be evident that the narrow slot in FIG. 8 will provide an ideal interconnection point between small semiconductor devices, such as mixer diodes, etc., and the waveguide circuit. Diodes can be directly integrated into the slot, FIG. 9, if desired, thus, reducing the external lead inductance of the device to zero. Wide band mounts may be realized in this way.

In certain applications narrow band mounts may be more convenient; provided the mount has a high unloaded Q-factor it may serve as the final resonator of an evanescent mode filter associated with the mount.

The loaded Q-factor may be raised by simply shortening the slot, which will then provide insufficient loading inductance to obtain transverse resonance. It will then be necessary to add a tuning screw in order to realize resonance. Clearly, a wide range of loaded Q's is obtainable by adjusting the ratio of these two parameters: slot length and tuning screw penetration. The practical range of loaded Q-factors obtainable in this way is from about 3 to 300, the upper limit depending on the unloaded factor of the resonator and the loss which may be tolerated. FIG. 10 illustrates the performance of a mount of medium bandwidth with slot and tuning screw.

To return now to the mixer arrangement of FIGS. 1, 15 2 and 3, the basic mount resonator may be coupled into on either side by, respectively, power from the signal and local oscillator sources. A third arm 6 on the outer broad face of waveguide 1 is necessary to prevent radiation from the slot. Image and sum termination circuits are placed in this arm.

The theory and practice of image termination has been discussed by several authors, Barber, M. R. "Noise Figure and Conversion Loss of the Schottky Barrier Mixer Diode," Trans. M.T.T. (I.E.E.E.) MTT-15, No. 11, Nov. 1967, and Johnson, K. M. "X-Band Integrated Circuit Mixer with Reactively Terminated Image." Trans. M.T.T. (I.E.E.E.) MTT-16, No. 7, July 1968. Johnson discusses various types of termination but shows that short-circuit termination has the incidental benefit of lowering the I.F. impedance.

Combined sum and short circuit image terminations produce substantial improvements in conversion loss, with corresponding improvements in noise figure.

In the mixer arrangement shown, the length of waveguide 6 is dimensioned to be below cut-off for the image frequency, i.e., it is evanescent at this frequency, and short circuit image termination is achieved quite simply with the capacitive screw 8. This evanescent mode resonator is tuned to resonate at image frequency, thus placing a short circuit across the terminals of the mixer diode 5. The length l between tuning screw 8 and the slot 3 determines the bandwidth over which the short circuit is maintained. The value is not critical, but if it is too short the match at local oscillator frequency will be affected. If l is too long the bandwidth of the mount will be inadequate.

Short circuit termination of the sum frequency is achieved in a different way. The size of the waveguide 6, which conveniently but not necessarily is the same size as that of waveguide 1, is chosen so that while the image frequency is below cut-off, the sum frequency is above cut-off. Thus, the latter frequency propagates in the usual way and a short circuit at the plane of diode 5 is achieved by locating plate 10 an appropriate distance from the diode (electrically half a wavelength bearing in mind that the presence of the capacitive screw will modify the physical distance necessary).

FIG. 11 shows a plunger 14 which for test purposes was used to replace plate 10 of FIGS. 1 and 3, and FIG. 12 shows the effect of varying the distance L of plunger 14 from diode 5, for a sum frequency of 15.243 GHz and $\lambda g/2 = 1.25$ cms (centimeters). It will be observed that the distance between maxima corresponds closely to the guide wavelength of the sum frequency in this guide. This is not a definitive test, however, because the local oscillator second harmonic is closely adjacent frequency. In order to confirm the theory it was therefore

necessary to interpolate a narrow-band band-pass filter between the diode and short circuit plunger. Measurements at, respectively, local oscillator and sum frequency (within each case the filter tuned to the appropriate frequency) then confirmed the theory.

The waveguide 7 of FIGS. 1 and 2 is constructed in rectangular cross-section guide which is beyond cut-off at the local oscillator signal frequency, and the capacitive screw 9 contained therein is adjusted to provide an evanescent mode rejection filter at that frequency. This rejection filter is not essential and will only be required if the local oscillator power is limited, to prevent power loss in the signal source.

The following performance figures of a mixer-local oscillator unit of the type shown in FIGS. 1, 2 and 3 are typical of the improvement which is obtained by the above-described image termination arrangement.

The first column figures are for an unterminated image, i.e., image absorbed in source, and the second column figures are for short circuit terminated sum and image frequencies.

Conversion Loss	4.5 dB	3.3 dB
Noise figure (calculated)	7.5 dB	6.3 dB
Noise figure (measured)	7.4 dB	6.1 dB
I.F. Admittance (normalized and related to a 50 ohm line)	0.12+j0.13	0.17+j0.03

These results were obtained with a Schottky barrier diode and are based on an I.F. noise figure of 2.5 dB (decibel) and a diode noise ratio of 1.2.

As already mentioned, the short circuit image termination has the desirable effect of lowering the IF impedance of the diode. The improvement, compared with resistive image termination, is shown in FIG. 13.

As an alternative to the above-described longitudinal slot, a transverse slot 15, FIG. 14, may be used. The principles involved with this transverse slot have much in common with those of the longitudinal slot, except that the transverse slot must be used above its natural resonant frequency, i.e., a length $>\lambda/2$. This is because the slot must present a series capacitive reactance, $X=2X_0$, in order to achieve evanescent mode resonance. A simple unloaded slot such as previously described would necessitate a length greater than the guide width, i.e., include the sidewalls, and therefore a dumb-bell slot is preferable. Although very similar to the previous arrangement there is less flexibility because the loaded Q-factor cannot be varied in the same way as with the longitudinal slot. Thus the transverse slot mount is likely to be of value in broad band applications.

In the above-described mixer arrangement, the use of waveguide both below cut-off and above cut-off permits the independent adjustment of the termination at sum and image frequency. Prescribed terminations can be obtained at frequencies approximately an octave apart, whereas using conventional wholly propagating waveguide techniques the sum frequency would be propagating in two modes and would, therefore, be unmanageable.

While we have described above the principles of our invention in connection with specific apparatus, it is to be clearly understood that this description is made only by way of example and not as a limitation to the scope of our invention as set forth in the objects thereof and in the accompanying claims.

We claim:

1. A waveguide mixer arrangement comprising:
a first waveguide, one end of which receives an input signal having a first given frequency and the other end of which receives a local oscillator signal having a second given frequency different than said first given frequency;
a first resonant slot disposed in one wall of said first waveguide intermediate the ends thereof;
said first waveguide including
a first evanescent mode waveguide filter to couple said input signal to said first resonant slot, and
a second evanescent mode waveguide filter to couple said local oscillator signal to said first resonant slot;
a second waveguide coupled at right angles to said first waveguide encompassing said first resonant slot, said second waveguide being dimensioned to be evanescent at the mixer generated image frequency and propagating at the mixer generated sum frequency;
a mixer diode disposed in said second waveguide adjacent to said first resonant slot;
a capacitive obstacle disposed in said second waveguide a first given distance from said first resonant slot to provide within said second waveguide an evanescent mode resonator tuned to said image frequency so as to effect reactive termination of said image frequency; and
a short circuit plate disposed in said second waveguide a second given distance greater than said first given distance from said first resonant slot to effect reactive termination of said sum frequency.
2. An arrangement according to claim 1, further including
a coaxial connector coupled to said second waveguide and said mixer diode; and
a low pass filter contained in said connector to extract the desired intermediate frequency signal which is equal to said first given frequency minus said second given frequency.
3. An arrangement according to claim 2, wherein
said first resonant slot includes
an unloaded narrow slot disposed parallel to the longitudinal dimension of said first waveguide.
4. An arrangement according to claim 2, wherein
said first resonant slot includes
a dumb-bell shaped slot disposed parallel to the transverse dimension of said first waveguide.
5. An arrangement according to claim 2, further including
a second resonant slot disposed in said one wall of said first waveguide adjacent said first resonant slot;
a third waveguide coupled at right angles to said first waveguide parallel to said second waveguide encompassing said second resonant slot, said third waveguide being dimensioned to be evanescent at said second given frequency, and
a capacitive obstacle disposed in said third waveguide a third given distance different than said first and second given distances from said resonant slot to provide an evanescent mode rejection filter for said second given frequency.
6. An arrangement according to claim 5, wherein
said first and second resonant slots each include

- an unloaded narrow slot disposed parallel to the longitudinal dimension of said first waveguide.
7. An arrangement according to claim 5, wherein said first and second resonant slots each include a dumb-bell shaped slot disposed parallel to the 5 transverse dimension of said first waveguide.
8. An arrangement according to claim 1, wherein said first resonant slot includes an unloaded narrow slot disposed parallel to the longitudinal dimension of said first waveguide. 10
9. An arrangement according to claim 1, wherein said first resonant slot includes a dumb-bell shaped slot disposed parallel to the transverse dimension of said first waveguide.
10. An arrangement according to claim 1, wherein a second resonant slot disposed in said one wall of said first waveguide adjacent said first resonant slot; 15 a third waveguide coupled at right angles to said first

20

- waveguide parallel to said second waveguide encompassing said second resonant slot, said third waveguide being dimensioned to be evanescent at said second given frequency; and a capacitive obstacle disposed in said third waveguide a third given distance different than said first and second given distances from said second resonant slot to provide an evanescent mode rejection filter for said second given frequency.
11. An arrangement according to claim 10, wherein said first and second resonant slots each include an unloaded narrow slot disposed parallel to the longitudinal dimension of said first waveguide.
12. An arrangement according to claim 10, wherein said first and second resonant slots each include a dumb-bell shaped slot disposed parallel to the transverse dimension of said first waveguide.
